Des. 1235

Nicholas S. Vedder, of Troy, N. Y.
Assignor to Sherman S. Jewett & J. H. Root, of Buffalo, N. Y.
Letters Patent No. 1235, dated April 24, 1860.

The schedule referred to in these Letters Patent and making part of the same.

To all whom it may concern:

Be it known that I, Nicholas S. Vedder, of the City of Troy, in the state of New York, have invented a new and original design for the ornamentation of a Cooking Stove, which is designated by the name of "The Improvement" of which the following in connection with the accompanying drawings is a full clear and exact description.

Fig. 1. Represents the front plate of a close front stove having two panels formed by a combination of "ogee" mouldings (a) and a center design consisting of an ovate ring (b) surmounted by adhuing embossed scroll work (c), centrally within this ring is an ovate boss (d) with a flane surface and bead (e) at its center and a scalloped ovate enclosure at its base. Rising from the midet of the scrolls at the extremes of the ovate ring (b) is a stem (f) supporting an inverted

crown (q) and urn (h) all in basso relief.

Fig. II. Represents a side plate with ornamented doors (I & t). The door (I) which opens into the fire chamber is surrounded by an "ogee" moulding. It has a cross central bead moulding (K) which divides the door into two panels.

The upper panel is ornamented with a design in relief like that already described on the front plate surrounding the stem (f) and crown (q), which are omitted and the urn or vase upon the extremes of the ovate ring (b).

The design is diminished in size to correspond with the size of the panel. The lower panel of the door is occupied by the sliding damper.

The upper part of the door (t) is surrounded and paneled by ogee mouldings similar to those of the front plate the panel being ornamented with the same design as the door (I) enlarged to correspond to the size of the panel.

The lower part of the door has a prolonged plane surface, (t) bevelled at (u) and a bead moulding (v) and ogee moulding (w) at the bottom.

Fig. III. Represents a side plate having a large oven door (I) which is surrounded and paneled by ogee mouldings and has a similar design on the panel made to correspond to the size of the door, as described in (Fig. I).

M. Represents a smaller oven door ornamented with similar mouldings and similar design on the panel in relief as already described in (Fig. II).

N. Represents a panel formed by similar mouldings and ornamented with a similar design in relief as described in (Fig. II) made to correspond to its size and position on the stove plate.

At (o) is represented a series of embossed rings.

Having thus described my design for a stove what I claim therein as new and desire to secure by Letters Patent is the ornamental design and configuration for the front and side plates of a stove as herein described and shown by the accompanying drawings.
